HAT SIZER

John W. Patterson, Jr., Sacramento, Calif.

Application June 19, 1950, Serial No. 168,908

10 Claims. (Cl. 2—183)

1

This invention is directed to, and it is a major object to provide, a hat band construction which automatically adjusts to the head size of the wearer; i. e. compensates effectively for variation in head sizes intermediate regular hat sizes, whereby to afford ease of fitting and great comfort to the wearer.

Another important object of the invention is to provide an automatic hat sizer which comprises a novel resilient and compressible assembly between the inner leather band and adjacent portion of the crown of the hat; such leather band being arranged to expand in circumference to permit the effective size of the hat to increase under conditions of head pressure on said band and resilient assembly.

A further object of the invention is to provide an automatic hat sizer, as above, wherein the resilient and compressible assembly includes—in one embodiment—an elongated cushion, of double-ended, wedge-like form, of foam rubber or the like secured in a novel manner between the inner band and crown, and—in another embodiment—includes a novel spring arrangement.

An additional object of the invention is to provide an automatic hat sizer which does not alter the appearance of a hat, or make any substantial increase in weight; the hat sizer being a compact assembly preferably disposed in the rear portion of the hat between the inner band and crown.

It is also an object of the invention to provide a hat sizer which is designed for ease and economy of manufacture, and being adaptable to present type hats, with a minimum of alteration.

A further object of the invention is to provide a practical and reliable hat sizer, and yet one which will be exceedingly effective for the purpose for which it is designed.

These objects are accomplished by means of such structure and relative arrangement of parts as will fully appear by a perusal of the following specification and claims.

In the drawings:

Fig. 1 is a perspective view of a hat, partially broken away, embodying the present invention.

Fig. 2 is a fragmentary enlarged plan view, partly in section, of the hat sizer, with the parts, including the inner head band, in their initial positions.

Fig. 3 is a similar view, but shows the hat sizer as compressed whereby to increase the circumference of the inner head band, and consequently enlarge the hat size.

Figs. 4, 5, and 6 correspond to Figs. 1, 2, and

2

3, but illustrate a modification of the inner head band.

Referring now more particularly to the characters of reference on the drawings, and at present to Figs. 1-3 inclusive, the novel hat sizer is here shown as embodied in a hat 1 of generally conventional construction, including a crown 2, a brim 3, and an inner head band 4 of leather or the like.

10 The inner head band 4 is in engagement with, and directly stitched to, the adjacent portion of the crown 2, as at 5, only about the forward part of the hat; substantially the rear half of the inner band 4 being initially separate from the crown 2, and spaced therefrom.

The numeral 6 indicates an elongated cushion strip of double-ended, wedge-like form disposed between the inner head band 4 and adjacent portion of the crown 2 about the rear part of the hat; said elongated cushion 6 being of foam rubber or the like, and—from the center rear point, which is relatively thick—tapering lengthwise towards opposite ends. The forward ends of the elongated cushion 6 terminate or run out adjacent, but short of, the corresponding ends of the line of stitching 5.

The elongated cushion 6 is preferably of constant height throughout, and is permanently affixed between the inner head band 4 and adjacent portion of the crown 2, near the bottom thereof, by a line of suitable stitching 7; each stitch being relatively large and formed with a cross thread 8 through the cushion crown and band 4.

30 35 The inner head band 4 is vertically split at the rear central point, as at 9, for the purpose of permitting circumferential expansion of said band.

The elongated cushion 6 is formed, on its outer face, with a relatively stiff facing F affixed thereto, as by cementing or vulcanization; the purpose of the relatively stiff facing F being to prevent any distortion or deformation of the adjacent portion of the crown 2 upon compression of said cushion 6.

40 45 The elongated cushion 6 and the adjacent attached portions of the head band 4 provide a resilient and compressible assembly which functions as follows to provide automatic hat sizing:

Upon the hat being placed upon the head of 50 a wearer, the inner head band 4 adjusts in circumference by reason of the split 9, the starting position of the hat band being shown in Fig. 2. The split 9 gaps to the extent necessary, as at 10, by reason of the compression when the hat is applied to the head, of the elongated cushion 6.

When the cushion is not compressed, as in Fig. 2, the cross threads 8 lie at substantially a right angle to said cushion. However, when the cushion is compressed, as in Fig. 3, the cross threads 8 slack and diagonal in the direction of movement of the corresponding portion of the inner head band 4 as it expands, whereby to not restrict such expansion.

The cushion 6 is of double-ended, wedge-like form, as hereinbefore described, to the end that maximum adjustment is accomplished mainly at the rear of the hat, with such adjustment being progressively less toward opposite sides of said hat.

The arrangement is such that the hat sizer provides automatic variation in the circumference of the inner head band 4 without in the least inconveniencing the wearer, and without any detraction from full comfort; the hat sizer not altering the appearance of the hat, and being a simple but effective addition thereto.

In Figs. 4, 5, and 6 the hat sizer is of the same construction as in Figs. 1-3, inclusive, including an elongated, double-ended, wedge-like cushion 11 between the inner head band 12 and adjacent portion of the crown 13; the cushion being secured to and between said parts by stitching 14. Here, however, the inner head band 12 is formed, at its rear central point, with a vertically corrugated section 15. The corrugated central section 15 of the inner head band 12 permits said band to expand or elongate in circumference, upon compression of the elongated cushion 11, both to the end that the effective hat size be increased. The head band or sweat band 12 may be split, with the split ends sewed together as usual, at any point in its extent. The stitching 14 does not extend along and through the corrugated section 15 of band 12, so as not to interfere with the expansion or contraction of said corrugated section 15.

The corrugated central section 15 of the inner head band 12 is initially as shown in Fig. 5 (the corrugations here being shown accentuated or enlarged for clarity), but when the elongated cushion 11 is compressed for the purpose of increasing head size, the corrugated central section 15 is expanded, as in Fig. 6.

In order that the corrugated central section 15 return to its initial position, as in Fig. 5, upon the elongated cushion 11 expanding, said section 15 is backed by an elastic strip backing 16 which extends across the section 15 between the adjacent non-corrugated portions of the head band 12. The elastic strip backing 16 is under tension when the section 15 is expanded, as in Fig. 6, and when the hat is being worn. Thereafter, when the hat is removed from the head the elastic strip backing 16 contracts the corrugated section 15 simultaneously with expansion of the elongated cushion 11. Thus, the inner head band 12 is maintained against wrinkling or other deformation.

The described hat sizer, in its several embodiments, provides a practical and reliable hat structure for accommodating a hat, automatically, to the head of a wearer, while maintaining comfort and appearance.

From the foregoing description it will be readily seen that there has been produced such a hat sizer as substantially fulfills the objects of the invention, as set forth herein.

While this specification sets forth in detail the present and preferred construction of the device, still in practice such deviations from such detail

may be resorted to as do not form a departure from the spirit of the invention, as defined by the appended claims.

Having thus described the invention, the following is claimed as new and useful, and upon which Letters Patent are desired:

1. An automatic sizer, for a hat which includes a crown and an inner head band secured within the crown, comprising a resilient and compressible strip between the inner head band and crown about a substantial circumferential portion thereof, the head band having a vertically corrugated section formed therein and disposed adjacent to and intermediate the ends of the strip, and means securing the strip in place without restricting circumferential elongation of the head band.

2. An automatic sizer, for a hat which includes a crown and an inner head band secured within the crown, comprising a resilient and compressible strip between the inner head band and crown about a substantial circumferential portion thereof, the head band including a vertically corrugated section disposed adjacent to and intermediate the ends of the strip, and means securing the strip in place without restricting circumferential elongation of the head band; there being an elastic tension strip backing the corrugated section of the band and connected to the adjacent uncorrugated parts of said band.

3. An automatic sizer, for a hat which includes a crown and an inner head band secured within the crown, comprising an elongated cushion, of resilient and compressible material, disposed between the inner head band and crown at one end and adjacent sides of the crown, a portion of the inner head band, adjacent to and intermediate the ends of the cushion, being arranged for circumferential elongation, and means securing the cushion to the crown and band without restricting such circumferential elongation of the latter attendant compression of the cushion; said securing means being stitching joining the crown, cushion and band and securing the cushion in place without restricting the circumferential elongation of said band, and the stitches being relatively large with cross threads which extend through the cushion at normally a substantially right angle.

4. An automatic sizer, for a hat which includes a crown and an inner head band secured within the crown, comprising an elongated cushion, of resilient and compressible material, disposed between the inner head band and crown at one end and adjacent sides of the crown, said cushion being double-ended and wedge-like in opposite directions from a central point, a portion of the inner head band, adjacent to and intermediate the ends of the cushion, being arranged for circumferential elongation, and stitching between the crown and band through the cushion to secure the latter in place.

5. An automatic sizer, for a hat which includes a crown and an inner head band secured within the crown, comprising an elongated cushion, of resilient and compressible material, positioned between the inner head band and crown at one end and adjacent sides of the crown, said cushion being double-ended and wedge-like in opposite directions from a central point, the inner head band being split vertically adjacent said point for circumferential elongation of the band, and stitching extending on either side of said split securing the cushion in said position in the hat.

6. An automatic sizer, for a hat which includes

a crown and an inner head band secured within the crown, comprising an elongated cushion, of resilient and compressible material, positioned between the inner head band and crown at one end and adjacent sides of the crown, said cushion being double-ended and wedge-like in opposite directions from a central point, the inner head band having a vertically corrugated section adjacent said point, and stitching extending on either side of said corrugated section securing the cushion in said position in the hat.

7. An automatic sizer, for a hat which includes a crown and an inner head band secured within the crown, comprising an elongated cushion, of resilient and compressible material, positioned between the inner head band and crown at one end and adjacent sides of the crown, said cushion being double-ended and wedge-like in opposite directions from a central point, the inner head band having a vertically corrugated section adjacent said point, and stitching extending on either side of said corrugated section securing the cushion in said position in the hat; there being an elastic tension strip backing the corrugated section of the band and connected to the adjacent uncorrugated parts of said band.

8. An automatic sizer, for a hat which includes a crown and an inner head band secured within the crown, comprising a strip of resilient and compressible material disposed between the inner head band and crown at one end portion thereof, the inner head band having a vertically corrugated section at said end portion, and means securing the strip to the hat and to the non-corrugated portion of the band so as not to restrict circumferential expansion of said vertically corrugated section of the inner head band.

9. An automatic sizer, for a hat which includes a crown and an inner head band secured within the crown; said sizer comprising, in conjunction with the inner head band and crown, a relatively short vertically corrugated portion formed in the band, a compressible strip secured in the hat and disposed back of said corrugated portion, and means securing the strip to the band beyond the ends of said corrugated portion.
10. An automatic sizer for a hat which includes a crown and an inner head band secured within the crown; the sizer comprising a resilient and compressible strip between the inner head band and the crown about a substantial circumferential portion thereof, a vertically corrugated section formed in the inner head band adjacent to and extending along the strip, and means securing the strip in place without restricting circumferential elongation of the inner head band.
